BIFURCATED SKIRT

Raymond F. Bowley, Boston, Mass.

Application July 28, 1950, Serial No. 176,287

4 Claims. (Cl. 2-212)

1

The present invention relates generally to improvements in women's nether garments and, as illustrated herein, relates more particularly to a bifurcated nether garment which presents the general appearance of a skirt.

This application is a continuation in part of my co-pending but now abandoned application for Slacks, Serial No. 16,500, filed March 23, 1948.

One object of the present invention is to provide an attractive and comfortable bifurcated nether garment which presents the general appearance of a skirt while retaining the comfort and freedom of a pair of "shorts" or "slacks." To this end, the garment is provided with front and back folds or pleats which overlie one leg portion at the front and the other leg portion at the back and which extend from the waist band to the bottom hem of the garment. As illustrated, the front portion of one leg portion is provided forwardly of the crotch portion with excess material which is folded to form a pleat which overlies the other leg portion and which extends upwardly to the waist band of the garment and is secured thereto. The back portion of the other leg portion is likewise provided with fold which overlies the first mentioned leg portion rearwardly of the crotch portion and which also extends upwardly to and is secured to the waistband of the garment at the back thereof.

There is provided by this invention a garment wherein increased fullness of material is provided on the inner portion of one front leg-section, and on the inner portion of the diagonally opposite back leg-section, this added fullness or enlargement being incorporated in a pleat or fold of material overlapping the corresponding adjacent leg-section from the median line of the garment and hanging in a straight line to the hem of the garment, giving the garment the freedom of slacks, and the appearance of a skirt by hiding the crotch seam while not interfering with the center front to center back direction thereof. Further advantageous features of this design reside in the placing of the garment closure at the front center and concealing the fastener thereof by the front fold. This placing of the garment closure in the center front permits a pocket to be included in each side seam.

In the drawings:

Figure 1 is a plan view of a pattern for the front sections of the present garment.

Fig. 2 is a plan view of the patterns used for making the front yoke and side pockets of the garment;

Fig. 3 is a view similar to Fig. 1 but showing 55 folds. Furthermore, the folded material of the

2

a pattern for the back sections of the garment;

Fig. 4 is a view in front elevation of the completed skirt of the present invention;

Fig. 5 is a view similar to Fig. 4 but showing the skirt in rear elevation;

Fig. 6 is a view in cross-section taken along the line 6-6 of Fig. 4;

Fig. 7 is a view in cross-section taken along the line 7-7 of Fig. 4;

Fig. 8 is a front perspective view of the completed skirt.

Referring now to the drawings, the present garment comprises a pair of right and left front leg sections 10 and 12, respectively, and a pair of right and left back leg sections 14 and 16, respectively. The right front and back sections 10 and 14 are suitably secured together at the outer sides, for example, by a line of stitching 18 (Fig. 7) while the inner edge portions thereof are secured together from the bottom to the crotch by a line of stitching 20. The left front and back portions 12 and 16 are suitably secured together by similar lines of stitching 22 and 24. The front crotch portions 26, 28 (Fig. 1) are stitched together to a point approximately five or six inches below the waist band to provide a suitable placket opening. The rear crotch portions 30, 32 (Fig. 3) are stitched together to the waistband. Thus, the four sections shown in Figs. 1 and 3 are secured together to form a garment having a pair of depending leg portions and which garment will be completed by the provision of a waistband, placket closure, pockets and suitable hems.

Referring now particularly to Figs. 1 and 3, it will be noted that the right front section 10 and the left back section 16 are substantially wider from top to bottom than the left front section 12 and the right back section 14. The material in the right front leg section 10 between the dot-dash lines 34, 36 is folded along the dotted line 38, to form a fold or pleat 38a (Figs. 6 and 7) which is located entirely forwardly of the crotch portion 26. The crotch portion is accordingly free from undesired pleats or folds since there is no excess material in this portion of the garment. When the two front sections 10 and 12 are stitched together, as described above, the fold or pleat 38a formed by the material between the lines 34, 36 overlies the left front section 12 throughout substantially the entire area between the dot-dash line 40 and the dotted line 42. This area lies entirely forwardly of the crotch portion of the left front leg section 12. Thus the crotch in both sections is free from undesired pleats or folds. Furthermore, the folded material of the

right front section conceals the median or crotch seam and overlies the vertical space between the leg portions and, hence the garment, as viewed from the front, presents the appearance of a skirt.

The left back section 16 is likewise wider from top to bottom than is the right back portion 14. The material between the dot-dash lines 44, 46 is folded along the dotted line 48 to form a fold or pleat 48a (Figs. 6 and 7) and when the garment is stitched together the fold or pleat 48a overlies the right back section 14 over substantially the entire area between the dotted line 50 and the dot-dash line 52 (Fig. 3). Thus when the wearer is in a normal standing position, the 15 garment from the back also appears to be a skirt.

The garment is provided with a usual waistband 54 which is preferably formed of the same material as the body of the garment and, as illustrated, is continuous. As previously stated, the crotch seam 26, 28 terminates at the front at a point five or six inches below the waistband. The unstitched portions form the edges of a placket opening located at substantially the front median line of the garment. This placket opening may be held closed by the use of any suitable fastener, such, for example, as the usual "zipper" which may be stitched to the sides of the opening. As is best shown in Fig. 6, the placket is concealed by the front fold or pleat 38a. Each of the leg portions 10, 12, 14 and 16, is provided with a dart 55, the edges of which are stitched to shape the garment at the waistline.

The garment is provided with a front yoke or lining which, as illustrated, is formed of two pieces 56, 58 (Fig. 2). These yoke pieces are stitched to the edge portions of the placket opening and extend outwardly toward the sides of the garment therefrom. The outer edge portion of each front piece at its lower side is stitched to the side seams 18, 22 of the garment while the remainder of each outer edge portion is stitched only to the back portions thus forming in effect a continuation of the side seams. The adjoining unstitched edges of the front portions 10 and 12 are stitched to pocket pieces 60, 62 (Fig. 2), the lower and inner edges of the pocket pieces being stitched to the underlying yoke pieces 56, 58 to form side pockets. The waistband 54, above referred to, is then stitched to the waist portion of the garment, including the upper edges of the yoke and pocket pieces. As illustrated, the waistband 54 is continuous and extends from the left edge of the placket opening around the back of the garment and back to the front of the garment terminating a short distance beyond the free edge of the pleat or fold 38a to form a tab 66 having a suitable fastener thereon for securing the tab to the underlying end portion of the waistband 54.

The garment presents the appearance of a skirt since the front and back pleats 38a, 48a conceal the space between the leg portions both at the front and at the back thereof. The folds or pleats 38a, 48a extend from the waistband 54 to the bottom of the garment and are located at the front and back of the garment, respectively. The material which joins these pleats is thus so located that it does not interfere in any way with either the use or the comfort of the garment. The crotch seam of the present garment, as best shown in Fig. 6, extends rearwardly at substantially right angles to the front of garment and is free from folds which would

make this portion of the garment bulky and hence uncomfortable to the wearer.

Having thus described my invention, what I claim as new and desire to secure by Letters Patent of the United States is:

1. In a garment providing the fit and general appearance of a skirt and the freedom of slacks, in combination, right and left members each having waist, body and leg portions, said members being secured to each other to form depending legs and a straight front-to-back crotch at the median line of the garment, one of said members having a wide vertical pleat in the front extending vertically from the waist portion to the bottom of the garment and laterally from adjacent the median line of the garment toward the other member and overlapping to a substantial extent the other member so as to conceal the space between the leg portions from the front, and the other member having a wide vertical pleat in the back extending vertically from the waist portion to the bottom of the garment and laterally from adjacent the median line of the garment toward the first member and overlapping to a substantial extent the first member so as to conceal the space between the leg portions from the back, said pleats providing enlargements of the respective leg portions.

2. In a garment providing the fit and general appearance of a skirt and the freedom of slacks, in combination, right and left members each having waist, body and leg portions, said members being secured to each other to form depending legs and a straight front-to-back crotch at the median line of the garment, the right member having a wide vertical pleat in the front extending vertically from the waist portion to the bottom of the garment and laterally from adjacent the median line of the garment toward the left member and overlapping to a substantial extent the left member so as to conceal the space between the leg portions from the front, and the left member having a wide vertical pleat in the back extending vertically from the waist portion to the bottom of the garment and laterally from adjacent the median line of the garment toward the right member and overlapping to a substantial extent the right member so as to conceal the space between the leg portions from the back, said pleats providing enlargements of the respective leg portions.

3. In a garment providing the fit and general appearance of a skirt and the freedom of slacks, in combination, a waistband, right and left members each having body and leg portions, said members being secured to said waistband and to each other to form depending legs and a straight front-to-back crotch at the median line of the garment, the right member having a wide vertical pleat in the front extending vertically from the waistband to the bottom of the garment and laterally from adjacent the median line of the garment toward the left member and overlapping to a substantial extent the left member so as to conceal the space between the leg portions from the front, and the left member having a wide vertical pleat in the back extending vertically from the waistband to the bottom of the garment and laterally from adjacent the median line of the garment toward the right member and overlapping to a substantial extent the right member so as to conceal the space between the leg portions from the back, said pleats providing enlargements of the respective leg portions.

4. In a garment providing the fit and general appearance of a skirt and the freedom of slacks, in combination, a waistband, right and left members each having body and leg portions, said members being secured to said waistband and to each other to form depending legs, a straight front-to-back crotch, and a front closure at the median line of the garment, the right member having a wide vertical pleat in the front extending vertically from the waistband to the bottom of the garment and laterally from adjacent the median line of the garment toward the left member and overlapping to a substantial extent the left member so as to conceal the closure and the space between the leg portions from the front, and the left member having a wide vertical pleat in the back extending vertically from the waistband to the bottom of the garment and laterally from adjacent the median line of the garment toward the right member and overlapping to a substan- 20

tial extent the right member so as to conceal the space between the leg portions from the back, said pleats providing enlargements of the respective leg portions. 5
